Primary Examiner — Calvin E Vansant*Assistant Examiner* — Mark T. Philipp(57) **CLAIM**

The ornamental design for an industrial robot part, as shown and described.

DESCRIPTION

The patent or application file contains at least one drawing executed in color. Copies of this patent or patent application publication with color drawing(s) will be provided by the Office upon request and payment of the necessary fee.

1. Industrial robot part

1.1 : Perspective

1.2 : Front

1.3 : Back

1.4 : Top

1.5 : Bottom

1.6 : Side

1.7 : Other side

1.8 : Perspective of the industrial robot part in a state of use

In the drawings, the broken lines depict environmental subject matter only and form no part of the claimed design. The portion of the design shown in the color dark coral is for the purpose of illustrating environmental subject matter only and forms no part of the claimed design.

The essential characteristics of the design are featured in its shape.

1 Claim, 8 Drawing Sheets
